UNITED STATES PATENT OFFICE.

WILLIAM G. DODGE AND CHARLES HORACE LEAVE, OF BOSTON, MASSACHUSETTS.

TELEPHONE-CALL REGISTER.

1,138,283.

Specification of Letters Patent.

Patented May 4, 1915.

Application filed March 20, 1914. Serial No. 826,109.

To all whom it may concern:

Be it known that we, WILLIAM G. DODGE and CHARLES H. LEAVE, citizens of the United States, and residents of Boston, county of Suffolk, State of Massachusetts, have invented an Improvement in Telephone-Call Registers, of which the following description, in connection with the accompanying drawing, is a specification, like 10 characters on the drawing representing like parts.

This invention relates to a device for registering telephone calls made by a telephone subscriber, and the object of the invention 15 is to provide a novel device of this nature which is located at the subscriber's station and in position to be observed by the subscriber, but which can be operated only from the central station, and then only 20 when the subscriber's receiver is off from the hook of his instrument.

The device comprises a recording instrument adapted to give a visual record of the 25 number of calls made, and means whereby this recording instrument can be actuated only from the central station by the operator and then only when the subscriber's receiver is off from his hook.

In using the device the subscriber will 30 get the central station in usual manner and put in his call, and when the connection is made, but just before the telephonic conversation takes place, the operator at central station will actuate the register thereby 35 causing it to count the call. The recording movement of the register can be seen by the subscriber and as the recorder is always in view, the subscriber can note whether or not his calls are correctly registered.

40 Our invention is a protection to the telephone company as it provides means for accurately registering the number of calls which a subscriber makes, and is also a protection for the subscriber because the recorder 45 cannot be operated except when the telephone receiver is off the hook, and, therefore, it will be impossible for the operator at the central station to actuate the recorder except when the subscriber's telephone 50 is being used, and when the subscriber

is in position to note the fact that the recorder is actuated.

In order to illustrate the invention we have disclosed in the drawing one embodiment thereof which will now be described, 55 after which the novel features will be pointed out in the appended claims.

Referring to the drawings, Figure 1 is a view showing diagrammatically a subscriber's telephone set and illustrating in diagram the application of our invention there- 60 to; Figs. 2 and 3 are different views of the recording device.

In Fig. 1 we have shown the telephone circuit and the subscriber's telephone set in diagram only, and 1 and 2 designate the two sides of the telephone circuit which leads from a central station and includes the subscriber's telephone set. This is shown in diagram only, and 3 indicates the transmitter, 4 the receiver, 5 the ordinary receiver hook on which the receiver is hung when the telephone is not in use, 6 and 7 the usual contacts with which the hook 5 engages when the receiver is taken off the hook and 75 by which the talking circuits are completed, and 8 represents the bell. These parts are all as usual in a telephone apparatus and need not be further described herein. It will be understood, of course, 80 that the telephone circuit 1, 2 is supplied with current from a suitable source of supply 9 located at the central station.

In applying our invention to a telephone circuit, we provide a circuit connection at 85 the subscriber's telephone set which is constructed to be connected automatically with one side of the telephone circuit when the receiver is taken off from its hook 5, and we further provide a recording device connected 90 to said connection, and means operable from the central station by the telephone operator to send a call-recording current through said side of the telephone circuit and said connection thereby to actuate the recorder. 95 In the construction herein shown this connection, which is designated 10, is a grounded connection, it being grounded at 11. It is provided with a contact 12 adapted to be engaged by the receiver hook 5 when 100

the latter is raised, said contact 12 being thus connected to the two sides of the telephone circuit.

Our improved recording device comprises an electro-magnet 13 connected in the grounded connection 10, a register or indicator 140, and means whereby the indicator or register will be advanced one step each time the magnet 13 is energized. As herein shown, said magnet 13 is mounted on a suitable base 15 and provided with an armature 14 pivoted to the base at 16. This armature has pivotally connected thereto a pawl or finger 17 adapted to engage a ratchet wheel 18 on one of the disks of the indicator or counter 140, the construction being such that each time the magnet 13 is energized and the armature attracted thereto the disk 14 will be turned forward one tooth. The register will have a plurality of indicating disks similar to an ordinary meter, the disks representing units, tens, hundreds, thousands, etc., and these disks will be actuated by the ordinary construction found in meters, but which is not herein shown, as it of itself forms no part of the present invention. The armature 14 is normally held in the position shown in Figs. 2 and 3 by means of a spring 18 which is herein shown as connected at one end to the armature and at the other end to an arm 19 secured to the base.

20 designates a stop screw adjustably mounted in a bracket 21 and by which the backward movement of the armature is limited, and 22 is another stop screw adjustably mounted in the armature by which the forward movement thereof can be limited. These two adjusting screws provide for adjusting the movement of the armature so that at each actuation thereof the indicator will be moved forward one step. The actuating finger 17 is shown as held in its operative position by means of a spring 23. In order to send the desired call-recording current through the grounded connection 10 from the central station, we have provided at the central station another grounded connection 24 having therein a source of current supply adapted to furnish current of the requisite volume and voltage to actuate the recording device. We have indicated such current supply diagrammatically by the battery 25, but any suitable source of current supply may be employed. This battery is shown as connected to the side 1 of the telephone circuit by means of a switch 26 situated to be operated by the telephone operator at the central station.

30 In the operation of the device the subscriber removes his receiver from the telephone hook and calls central station in the usual manner. In thus removing the telephone receiver the grounded connection 10 is connected to the telephone circuit but be-

cause of the presence of the magnet 13 in said connection and the fact that said connection is grounded the normal currents in the telephone circuit 1 and 2 are not disturbed, nor does the presence of this grounded connection interfere with the ordinary telephone operation. After the operator has connected up the subscriber with the party to whom he wishes to talk, said operator will then close the switch 26 momentarily, thus completing a recorder-operating circuit comprising the connection 24, battery 25, side 1 of the telephone circuit and grounded connection 10. By this act the current from the source of supply 25 will be sent through the magnet 13 of the recording device, and this current is of sufficient volume and strength to actuate this magnet. The energization of the magnet 13 advances the recorder one step, thus causing indication of the fact that a call has been made. This recorder will be placed in position where it can be observed by the subscriber, and he can, therefore, note the fact that the call has been registered. Further, the actuation of the recording device will produce a click or other noise which the subscriber can readily recognize. Moreover, it will be noted that the grounded connection 10 is disconnected from the telephone circuit, and therefore the recorder is rendered inoperative so long as the receiver is on the hook 5, and hence it is impossible for the operator at the central station to actuate the subscriber's recording device without the subscriber's knowledge.

Having described our invention, what we claim as new and desire to secure by Letters Patent is:—

1. In a telephone call recorder, the combination with a telephone circuit including a subscriber's telephone set, of an electrically-actuated call recorder, a circuit therefore normally continuous through said recorder and having a terminal situated to be engaged by the hook of the subscriber's instrument when the receiver is removed therefrom whereby the removal of the receiver will automatically connect said call recorder circuit to one side of the telephone circuit, and means operable from the central station to supply to said side of the telephone circuit and call recorder circuit a current of sufficient volume to operate the latter without interfering with any conversation being carried on over the telephone circuit.

2. In a device of the class described, the combination with a telephone circuit including a subscriber's telephone set, of a grounded normally continuous connection having a terminal situated to be engaged by the hook of the subscriber's set when the receiver is removed therefrom whereby said grounded connection is connected to one side of the telephone circuit; an electrically-actuated recording device in said grounded connection,

and means at the central station to send through said side of the telephone circuit and the grounded connection a call-recording current of sufficient volume to operate 5 the recording device without interfering with any conversation being carried on over the telephone circuit.

In testimony whereof we have signed our

names to this specification in the presence of two subscribing witnesses.

WILLIAM G. DODGE.

CHARLES HORACE LEAVE.
